UNITED STATES PATENT OFFICE.

RALPH E. MARBURY, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRODE FOR ELECTROLYTIC CONDENSERS.

Application filed October 27, 1920. Serial No. 419,798.

To all whom it may concern:

Be it known that I, RALPH E. MARBURY, a citizen of the United States, and a resident of Wilkinsburg, in the county of Allegheny and State of Pennsylvania, have invented a new and useful Improvement in Electrodes for Electrolytic Condensers, of which the following is a specification.

This invention relates to electrodes, more particularly to electrodes formed of corrugated or folded sheet metal and especially adapted for use in electrolytic condensers, lightning arresters, rectifiers and the like.

The present invention is closely related to the invention described and claimed in the copending application of Aalborg, filed Oct. 23, 1920, Serial No. 419,025, and assigned to the Westinghouse Electric & Manufacturing Company.

In the aforesaid application, there is described an improved electrode formed of a sheet of metal which has been so cut as to produce a series of sections with integral intermediate spacing members, the entire structure being folded to provide a large area exposed to an electrolyte, this area being contained in a relatively small space. Such construction presents many advantages over those previously proposed, and the present invention is a modification of the invention of Aalborg designed to more perfectly eliminate the disadvantages of prior electrodes.

One of the objects of the present invention is to provide an electrode structure of the type above mentioned which is rigid and rugged, which presents no sharp edges, and that is compact.

A further object of this invention is to provide an electrode of peculiar form such that the areas of the various sections comprising the electrode increase from the edges thereof to the center.

In practising my invention, I provide a sheet of metal and cut therein a series of slots having the form of segments of a circle. These segments form sections resembling a series of disks, each of the disks being united to the next by a constricted portion integral therewith. The sections so formed are then folded, being spaced from each other by intermediate spacing members formed in the cutting operation and serving to prevent the various sections from

coming in contact with each other, thus preventing impeding of the circulation of the electrolyte.

By providing a series of sections in parallel, the area of each of the sections increasing from the edge to the center, I form an electrode in which the current density from the edge to the center is substantially constant, thereby causing current to more readily penetrate the interior of the electrode, and utilizing the entire area of the electrode more effectively. Preferably, I provide holding means formed integrally with the body of the electrode, and I also provide conducting leads cut from the same metal sheet.

Referring to the accompanying drawings forming a part hereof, in which similar reference characters denote similar parts, and which illustrate one embodiment of my invention,

Fig. 1 is a plan view of a sheet of metal cut in accordance with my invention and ready to be folded;

Fig. 2 is an end view of a folded electrode, and

Fig. 3 is a side view of the same.

A sheet of metal 1 has a series of slits 2 cut therein as shown in Fig. 1, the slits extending practically across the entire face of the sheet. Generally such slits are in the form of sectors of a circle, the center of which is midway between two oppositely curving slits. By so cutting the sheet, there are formed a series of disks 3 united by intermediate connecting portions 4 forming a section of the electrode. Each of the sections is separated from the next one by an intermediate spacing member 5. Extended portions 6 are formed at various intervals along the edges of the sheet, apertures 7 being provided therein so that when the sheet is folded, all the apertures are in alinement. At each end of the sheet, cuts 8 are made.

The sheet is then folded or corrugated along lines 9 and 10 to form the body portion of the electrode, as shown in Figs. 2 and 3. The face of one section then lies opposite the face of the adjacent section, that is, the several sections are in parallel. Conducting leads 12 and 13 formed along cuts 8 are bent in opposite directions on lines 11. Rods 14 are threaded through openings 7 which are in alinement and may

be secured in fixed relation by any suitable means, such as welding.

An electrode so constructed is very sturdy and rigid even without the aid of clamping or holding members, and is easy to construct, since it requires but a few simple cutting and bending operations to form the completed structure. On account of the inherent resiliency of the metal, the various folds tend to separate, leaving the adjacent sections out of contact with each other, thereby still further increasing the surface area exposed to the electrolyte over that of prior structures. At the same time, short-circuiting is prevented, thus increasing the efficiency of the electrode.

Although I have above described in detail a specific embodiment of my invention, it is to be understood that my invention is not limited to the details shown, since it is obvious that various changes may be made in the construction of my improved electrode within the scope of my invention. For instance, the relative dimensions of disks 3 and connecting portions 4 may be varied, the portions 4 may be omitted altogether, if desired, and various other changes of proportions, such as narrowing or widening of intermediate spacing members 5 relative to disks 3, may be made.

Disk 3 need not necessarily consist of segments of circles but various other forms, such as ellipses, etc., may be substituted therefor, the prime requirement being that the area of each section shall increase from the edge thereof to the center. The holding and clamping means need not be as described but various other well known holding and clamping means may be substituted therefor. These and other changes may be made in the structure without departing from the scope of my invention which it is desired

to claim broadly except as limited by the claims appended hereto.

I claim as my invention:

1. An electrode comprising a series of disks integrally formed.

2. An electrode comprising a series of disks integrally formed and arranged in parallel sections.

3. An electrode comprising a series of disks arranged in parallel sections, each section including a plurality of disks.

4. An electrode comprising a series of disks, each of said disks being united to the next by a constricted portion.

5. An electrode comprising a series of disks, each of said disks being united to the next by a constricted portion integral therewith.

6. An electrode comprising folded sheet metal providing sections united by intermediate spacing members, the area of said sections and of said intermediate spacing members increasing from their edges to the center.

7. An electrode comprising folded sheet metal providing sections united by intermediate spacing members, extended portions on the upper and lower ends thereof, apertures therein, and means threaded therethrough for holding the sections of said electrode.

8. An electrode comprising a series of disks arranged in parallel sections, each section including a plurality of disks, the face of one section being opposite to the face of an adjacent section, and a single intermediate spacing member therebetween.

In testimony whereof, I have hereunto subscribed my name this 13th day of October, 1920.

RALPH E. MARBURY.
